(57) **CLAIM**

The ornamental design for a charging station for electric vehicles as shown and described.

DESCRIPTION

The patent or application file contains at least one drawing executed in color. Copies of this patent or patent application publication with color drawing(s) will be provided by the Office upon request and payment of the necessary fee.

1.1 : Perspective

1.2 : Front

1.3 : Left

1.4 : Right

1.5 : Back

1.6 : Top

1.7 : Bottom

2.1 : Perspective

2.2 : Front

2.3 : Left

2.4 : Right

2.5 : Back

2.6 : Top

2.7 : Bottom

The key features lie in the appearance of the product.

The broken lines in the reproductions illustrate portions of the charging station for electric vehicles that form no part of the claimed design.
